his ATTORNEY

UNITED STATES PATENT OFFICE.

CHARLES DÜRRIGL, OF VIENNA, AUSTRIA.

MULTICOLOR-LIGHT-EMITTING LAMP.

Application filed August 27, 1921. Serial No. 496,055.

To all whom it may concern:

Be it known that I, CHARLES DÜRRIGL, subject of the Republic of Austria, residing at Vienna, III., Untere Viaduktgasse Nr. 35, Austria Republic, have invented certain new and useful Improvements in Multicolor-Light-Emitting Lamps, of which the following is a specification.

This invention relates to multicolor light emitting lamps more particularly for advertising purposes and has for its object to provide lamps permitting of varying the color of the light emitted by them in more or less rapid succession and suddenly or gradually and at the same time to increase the number of colours of the light so emitted. In apparatus of this class as heretofore constructed more particularly for advertising purposes, either fixed lamps provided with reflectors and coloured cylinders or bulbs were used or movable coloured screens were used. The colour effects obtained by the first named class of apparatus are too monotonous for advertising purposes as they produce only light of one colour; the apparatus of the second named class produces more variegated effects which, however, are still too monotonous, a small number of colours following successively always in the same order. In order to provide for more attractive and striking effects than could be secured by the apparatus used heretofore I provide a light emitting body and a multicolor transparent screen surrounding the light emitting body in the optical axis of a reflector and means for moving such screen in the direction of the said optical axis, whereby by simply varying the movement of the said screen the colours of the light emitted by the reflector may be varied in number and sequence within very wide limits, more or less suddenly or gradually. Another object of this invention is to provide a simple and cheap apparatus of this class.

In the annexed drawings various embodiments of the present invention are shown by way of example.

Figs. 1 and 2 are a vertical section and front elevation respectively of the improved lamp.

Figs. 3 and 4 show side elevations of screens used in these lamps.

Figs. 5, 6 and 7 are a front elevation, a transverse vertical section and a sectional

plan respectively of an apparatus provided with the improved multicolor light emitting lamps.

Figs. 8 and 9 show a letter composed of the improved lamp in front elevation and vertical section respectively.

As shown in the drawings the light emitting body 1 such as the filament of an electric incandescent lamp is arranged in the optical axis of a reflector 2 which may be more or less curved or even plane as circumstances may require. 3 is a transparent screen for instance of stained glass showing a variety of colours distributed over the same in any desired manner. In the case of an electric incandescent lamp this screen may be the bulb of the lamp itself as shown in Fig. 3; in case of other lamps the screen may be a structure independent of the light emitting body as shown in Fig. 4. This screen is arranged in the optical axis of the reflector 2 and is operated to reciprocate in the direction of such axis, as indicated by the arrow in Fig. 1, by any suitable gearing. The different colours desired may be distributed over the screen in any suitable manner, for instance in helical strips as shown in Figs. 3 and 4.

As long as the screen is at rest the reflector emits light of different colours simultaneously, and in the case of the distribution of the coloured strip illustrated by Figs. 3 and 4 different sectors of the reflector 2 emit light of different colours. If now the screen is reciprocated in the direction of the arrow Fig. 1 the colour of the light emitted by any individual part or sector of the reflector varies continuously thereby producing a novel and most attractive effect. Instead of the screen the reflector may be reciprocated, as all that is required is that the screen and the reflector reciprocate relatively to each other.

Multicolor light emitting lamps as above described may be used in connection with any existing advertising devices as for instance inscriptions or pictures to be exhibited as illustrated in Figs. 5 to 9.

The inscription or picture table 11 shown in Figs. 5 to 7 is mounted in a box 10 and shows for instance the inscription REX; in rear of each of the letters a reflector 2 is supported on a plate 12 and the light screens 3 are secured to a reciprocating slide 13 running on guides 14 and actuated by con-

necting links 15 and cranks 16 operated by a motor, preferably a small electric motor 17 through the medium of suitable gears 18, 19; in this way the screens are reciprocated relatively to the reflectors whereby the letters of the inscription show the varying light effects above described.

The letter shown in Figs. 8 and 9 is composed of a plurality of light emitting bodies 10 and reflectors suitably assembled in any known or preferred manner, the reflector being secured as is seen from Fig. 9 on a supporting plate 20 and the screens 3 are secured to a slide 21 in rear of and reciprocated relatively to the supporting plate 20 by any suitable mechanism not shown.

In order that during sunshine while the lamp is not burning a clearly distinguishable multicolor reflexion effect may be secured. 20 The screen is provided with an uncoloured transparent tip 31 as shown in Fig 3 which permits the screen to receive in its inside light directly from the sun.

The mechanism for reciprocating the reflectors or the screens may be varied at 25

will without departing from the essence of the present invention.

Claims:

1. In an advertising device, the combination with a reflector, of a body adapted to emit light and located in the optical axis of the reflector, a multicolored transparent screen surrounding such light emitting body and automatically operating means for continuously reciprocating such screen relatively to the reflector in the direction of the optical axis thereof. 35

2. In an advertising device, the combination with a reflector, of a body adapted to emit light and located in the optical axis of the reflector, a substantially cylindrical transparent screen surrounding such light emitting body and having thereon a plurality of transparent helical strips of different colours and automatically operating means for continuously reciprocating such screen relatively to the reflector in the direction of the optical axis thereof. 45

CHARLES DÜRRIGL.
